CLAIM

The ornamental design for a note holder, as shown and described.

DESCRIPTION

FIG. 1 is a perspective view of a note holder showing my new design;

FIG. 2 is a front view thereof;

FIG. 3 is a top view thereof;

FIG. 4 is a bottom view thereof;

FIG. 5 is a right side view thereof;

FIG. 6 is a left side view thereof;

FIG. 7 is a perspective view of the note holder of FIGS. 1-6 differing only in the disclaimed regions;

FIG. 8 is a front view thereof;

FIG. 9 is a top view thereof;

FIG. 10 is a bottom view thereof;

FIG. 11 is a right side view thereof;

FIG. 12 is a left side view thereof;

FIG. 13 is a perspective view of the note holder of FIGS. 1-12 differing only in the disclaimed regions;

FIG. 14 is a front view thereof;

FIG. 15 is a top view thereof;

FIG. 16 is a bottom view thereof;

FIG. 17 is a right side view; and,

FIG. 18 is a left side view thereof.

The broken line showing of the remainder of the note holder is for environmental purposes only and forms no part of the claimed design.
